C. L. Taylor *INVENTOR*
By Seymour Wright *Attorney*

UNITED STATES PATENT OFFICE.

CLARENCE L. TAYLOR, OF ALLIANCE, OHIO, ASSIGNOR TO THE MORGAN ENGINEERING COMPANY, OF ALLIANCE, OHIO.

METHOD OF AND APPARATUS FOR STRAIGHTENING ROLLED ENDLESS BILLETS.

1,420,785.

Specification of Letters Patent. Patented June 27, 1922.

Application filed November 5, 1919. Serial No. 335,901.

To all whom it may concern:

Be it known that I, CLARENCE L. TAYLOR, a citizen of the United States, and a resident of Alliance, in the county of Stark and State of Ohio, have invented certain new and useful Improvements in Method of and Apparatus for Straightening Rolled Endless Billets; and I do hereby declare the following to be a full, clear, and exact description of the invention; such as will enable others skilled in the art to which it appertains to make and use the same.

My invention relates to an improvement in method of and apparatus for straightening rolled endless billets.

This apparatus is designed for cutting endless blanks or billets and then straightening them to form billets for rolling into railroad rails, and it consists in the method of converting a piece of metal, annular in form into a straight section and also to the apparatus and in the details of construction of such apparatus as will be more fully described and pointed out in the claims.

In the accompanying drawings, Figure 1 is a view in plan of my improved apparatus; Figure 2 is a view in side elevation of the straightening machine and Figure 3 is an end view of one of the roller bearings on the base or frame of the straightener.

5 represents a base plate secured to a suitable foundation by bolts 6, and 7 is a motor secured to the base adjacent one end thereof and geared by the pinions 8—9 and 10 to the pinion 11 on shaft 12. This shaft is mounted to rotate and also move longitudinally in the bearings 13 and 14, and the pinion 11 is located intermediate the said bearings and is in mesh with the long pinion 10 which is secured on shaft 15. Shaft 12 is threaded as at 16 and this threaded portion engages a threaded bushing in bearing 14, so that when the shaft is rotated by the motor it will also be moved longitudinally, the direction of longitudinal movement being dependent on the direction of rotation of the motor 7. Swiveled to the inner or threaded end of the shaft 12 is the yoke shaped bearing 17 which is mounted and guided for sliding movement on the base 5. This bearing 17 carries the horizontal grooved roller 18, which, as will be hereinafter explained, is adapted to engage the billet after the latter has been cut, and by forcing it against

two positively driven grooved rollers 20 and 21 straighten the billet.

The grooved rollers 20 and 21 are secured respectively to the upper ends of the vertical shafts 22 and 23, which latter, as shown in Figure 2 are supported above the table 60 in the yoke shaped bearing 24, the rollers 20 and 21 being within and partly housed by said bearings. These shafts extend through the bed 5 and into a pit below the bed, and shaft 22 is provided with a bevel pinion 25 which meshes with a similar pinion 26 on the horizontal shaft 27. This shaft 27 is supported at its outer end in bearing 28 and carries the large gear wheel 29 which is in mesh with pinion 28 on shaft 70 29^a, the latter having pinion 30 at its outer end which is in mesh with pinion 31 on the armature shaft of the motor 32.

Shaft 22, which as before explained carries the bevel pinion 25, is also provided with pinion 33 which meshes with pinion 34 on an idler shaft 35 located parallel to the vertical shafts 22 and 23, and pinion 34 is also in mesh with pinion 36 on shaft 23, so that when motion is imparted to shaft 22, shaft 23 will be turned in the same direction thus rotating the feed rollers 20 and 21 in the same direction at the same speed.

The bed 5 is provided with a series of horizontal radially disposed rollers 33^a, 85 which latter support the endless blank or billet 39, shown in dotted lines in Figure 1, so that it will move freely and without undue friction when in contact with the feed rolls 20 and 21 and the straightening roll 18. 90

The table 5 is provided at one side with a slot 35^a for the entrance of the saw 36^a. This saw is mounted on a sliding carriage 36^b, and is driven by a motor and gearing or by a belt as may be preferred. The saw 95 is located at the side of the frame 5 in line with the slot 35^a, and normally is entirely outside of said slot and is moved into the slot to sever the endless billet 34.

In the operation of the apparatus the 100 ring shape or endless billet is formed in a tire or similar mill, as described in my application, above referred to, and is entered between the rolls 18—20 and 21 as shown in dotted lines, the roller 18 being withdrawn 105 or moved outwardly to permit of the introduction of the billet between said rolls, and is afterwards moved into contact with the

billet to hold it in place while being cut by the saw. After it has been severed transversely, motion is imparted to the feed rolls 20 and 21 to turn the billet, which as shown 5 is supported on the rollers 33^a and by the rolls 18—20 and 21, until the cut end has passed the roll 20 and is in engagement with roll 21 as shown in full lines in Figure 1. Power is then applied to screw 12 to turn 10 same in a direction to force the straightening roll 18 against the billet to straighten the same, after which the feed rolls are started and the billet is fed between the feed rolls and the straightening roll. As the billet is 15 straightened, its straight end passes onto the roller table 37 and is carried off by the latter, and may be then rolled into a railroad rail or other article.

It is evident that many slight changes 20 might be resorted to in the relative arrangement of parts shown and described without departing from the spirit and scope of my invention. Hence I would have it understood that I do not wish to confine myself to 25 the exact construction and arrangement of parts shown and described, but

Having fully described my invention what I claim as new and desire to secure by Letters-Patent, is:—

- 30 1. In an apparatus for straightening rolled endless billets, the combination of a horizontal support for the endless billet, two positively driven feed rolls adapted to engage the inner face of said billet, an idler straightening roll co-acting with said positively driven rolls and adapted to engage the outer face of the billet, means for moving the straightening roll toward and away from the feed rolls, and cutting means movable toward the endless billet for severing the same prior to the movement of the billet between the feeding and straightening rolls.
- 35 2. In an apparatus for straightening rolled endless billets, the combination of a series of radially disposed horizontal rollers for supporting an endless billet; two positively driven feed rolls to engage one face of said billet, an idler straightening roll to engage the other face of said billet in a plane between the feed rolls, means for moving the straightening roll toward and away from the

feed rolls, and a cutter for severing the endless billet prior to the movement of the same between the feeding and straightening roll.

55

3. In an apparatus for straightening rolled endless billets, the combination of a horizontal support for the endless billet, two positively driven feed rolls to engage one face of the billet, an idler straightening roll 60 engaging the opposite face of the billet in a plane between the two feed rolls, a screw for moving the idler roll toward and away from the feed rolls, a motor and gearing for rotating said screw and a cutter movable toward the billet for severing it prior to its movement between the feeding and straightening rolls.

65

4. In an apparatus for straightening rolled endless billets, the combination of a series 70 of horizontal supporting rollers arranged to support a ring shaped endless billet, two positively driven vertical shafts each carrying a feed roll, a straightening roll coacting with the feed rolls and located in a plane 75 intermediate the latter, a screw for moving the straightening roll toward and away from the feed rolls, and a cutter movable toward the billet for severing same.

75

5. The method of converting a piece of 80 metal, annular in form, into a straight section, which comprises squeezing a portion of the annular piece between rolls so as to straighten said portion, and then driving the rolls so as to run the piece through the rolls 85 and straighten it from end to end.

85

6. The method of converting into a straight section an annulus, transversely slotted at one point, which consists in squeezing a portion of the annulus adjacent the point of the 90 slot between rolls so as to straighten said portion, and then driving the rolls so as to run the piece through the rolls and straighten it from end to end.

90

In testimony whereof, I have signed this 95 specification in the presence of two subscribing witnesses.

CLARENCE L. TAYLOR.
